FULLING MILL

Frank B. Morrill, North Adams, Mass., assignor to
 The James Hunter Machine Company, North
 Adams, Mass., a corporation of Massachusetts

Application April 11, 1946, Serial No. 661,459

34 Claims. (Cl. 26—21)

1

The fulling of cloth is effected by subjecting the cloth in roped or rolled form to alternate pressure and release in the presence of heat and moisture, customarily with the addition of soap to lubricate the fibers and facilitate the fulling thereof. A standard method of effecting this alternate pressure and release and the generation of heat is through the use of opposed rolls rotated to feed the cloth in rope form through their nip and pressed together to subject it to heavy pressure thereat, each length of cloth being looped through the rolls in two or more slack loops and having its ends sewed together so that all the loops are endless. The rolls are then driven continuously to feed the cloth round and round constantly in one direction of travel until the fulling is completed, the rolls fulling the cloth in the direction of its width, while crimp boxes which resist the discharge of the cloth from between the rolls and thus compel the cloth to force its way out of the crimp boxes and form itself into transverse pleats or folds within the boxes effect the lengthwise fulling of the cloth. The rolls never reverse their direction of rotation, because the nature and construction of the crimp box do not permit reversal of the direction of travel of the cloth.

In the conventional fulling mill of this type, the rolls, crimp boxes, guides, and other parts working on the cloth are enclosed in a housing whose main function is to hold those portions of the cloth which are not at the moment passing through the rolls and crimp boxes, but which are undergoing the periods of relaxation and opening up which must necessarily alternate with the momentary widthwise and lengthwise compression as essential steps in the fulling process.

As thus indicated, the fulling of cloth is not an instantaneous action, and in all known processes requires this repetition of alternate pressure and relaxation which consumes an extended period of time.

Hitherto all roller type fulling mills, so far as I am aware, have been batch or piece mills, into which the entire load of cloth to be fulled is put before the fulling operation is started, and out of which no fulled cloth is obtainable until the fulling of the entire contents is completed, and then the entire load is taken out at once. As is well known, these mills require the expenditure of a very considerable amount of time and effort to separate the rolls and enter the cloth and distribute the loops through their guides, and to sew together the ends of the cloth to make the loops endless; it sometimes takes $\frac{1}{2}$ hour to load 10 or 12

2

cuts of cloth into a mill and put the ends together, for an actual run of the mill of from 5 minutes to $\frac{1}{2}$ hour, and thus it takes as long or several times as long to get the cloth in as is spent in the useful operation of the mill. In addition, further time is lost through having to stop the mill periodically to change the positions of the various ropes of cloth or to turn the pieces end for end, to avoid the formation of creases and wrinkles and to equalize the fulling, and also in cutting apart and removing the cloth when the fulling is finished, at which time the mill is also standing idle.

This prior type of mill, besides involving a laborious and time-consuming process of loading and unloading with the machine's production suspended, of course does not fit into any continuous series of cloth-finishing operations.

The main purpose of the invention is to provide a novel and improved method and apparatus for fulling which will effect a substantially unlimited continuous discharge of cloth fulled to any desired extent, thus supplanting the prior batch system by a process of complete warpwise and weftwise fulling which can be incorporated with other finishing operations to produce a straight-line or continuous system. However, since fulling is not an instantaneous process effected by compression alone, and time is an essential factor involved in the need for relaxation and opening up periods alternating with compression, it would be impracticable for most purposes to build fulling apparatus with enough pairs of rolls to effect the necessary number of nips, which may be anywhere from 50 to 100 or more, with space for depending bands of relaxed cloth intervening between the pairs of rolls, in the effort to produce fulling apparatus in which the cloth would be merely fed in one side and out the other. This and other problems met with in such a proposal make it impracticable.

In accordance with the invention, therefore, and to solve the problem of subjecting the cloth to the necessary number of nips or compressions with intervening relaxation periods while still feeding the cloth substantially continuously through and out from the machine, the cloth is fed through opposed fulling rolls compressing the cloth between them and through a succeeding crimp box, and then is fed reversely through the same or other opposed fulling rolls and a succeeding crimp box to a slightly lesser extent of travel, whereby through feeding it back and forth repeatedly through the rolls and crimp boxes as many nips may be given to the cloth and as much

fulling performed thereon as desired, while obtaining at the end of each cycle of one backward and one forward feed an output of several yards of cloth fulled completely both widthwise and lengthwise.

Thus, for a simple example, if a 60-yard cut of cloth is threaded through the mill without looping and is fed forward through the mill by a pair of opposed rolls at the rate of 180 yards per minute for its entire length of 60 yards, and hence passes through the mill in $\frac{1}{3}$ minute, and then the direction of feed is reversed for 59 yards at the same speed, and this differential feed in alternate directions kept up, a net advance or output of the cloth of one yard of completely fulled material is obtained every $\frac{2}{3}$ minute, representing the length which has failed to re-enter the nip of the rolls. By the use of a leader, preferably one of the cuts themselves requiring to be fulled, to which the starting end of a given cut to be fulled is attached, at least equaling the length of the amount of reverse feed adopted for the machine, which may be any desired figure, and with a succeeding cut of cloth to be fulled attached to the trailing end of this original cut, the same number of nips can be applied to each unit of length of the given cut of cloth, and thereafter to any succeeding cut of cloth which may be attached thereto and followed by a suitable length of cloth to prevent unthreading. In practice, the cut of cloth which is used as the leader is taken off from the leading end of the string of cuts being fulled after this cut has passed completely through the mill, and its leading end is attached to the trailing end of the string of cuts. This leader cut has not been uniformly fulled in its passage through the mill at the head end of the string, since the first yard thereof has only received one nip while the succeeding yards have received a progressively increasing number of nips up to the final yard, which has received the full complement of say 120 nips. Hence by transposing it to the end of the string without reversing its direction of extent, and stopping the fulling when the trailing end of this cut of cloth has again reached the fulling rolls, an additional number of nips grading from 120 nips on the leading yard to one nip on the last yard is administered to this cut, thus rendering the fulling of this cut uniform from end to end and equal to the fulling of the rest of the cuts forming the string.

When this leader cut exceeds in length the yardage required for the backward feed for which the mill is set, a mark is placed in this cut just outside the feed end of the machine after the length thereof required for the backward feed has been fed into the mill and through the fulling rolls. Then after this leader cut is transferred to the trailing end of the string, the fulling is stopped when this mark again arrives in its initial position at the feed end of the mill and thus indicates that the additional fulling needed to full every yard of this cut equally has been completed.

In this manner a steady output of fulled cloth is obtained from the mill on the above basis at the rate of one yard each $\frac{2}{3}$ minute, each yard of which has been subjected to substantially 120 nips or passes between the rolls.

The difference between the length of forward and backward feed depends on the amount of fulling and the consequent length of time desired to be given to the particular cloth; where less fulling is required, an increase in the forward

feed to 61 yards, for example, will give an output of 2 yards each $\frac{2}{3}$ minute; the differential between the forward and reverse feeds represents the output of each cycle.

The cloth is either passed through the mill in straight and parallel runs, or is looped through the rolls in double or triple passes, as heretofore in conventional mills, the looping thus doubling or tripling the number of nips effected during the travel in each direction, permitting a corresponding increase over the example just given in the output of the mill at the end of each cycle of one forward and one backward feed, and attained by an appropriate increase in the differential between the reverse feed and the forward feed. The cloth automatically shifts its position between the rolls, rendering the fulling uniform, and the desired reversal of travel previously requiring stopping of the mill and taking the pieces out and turning them end for end to prevent the setting of creases and wrinkles likewise occurs automatically because inherent in the process.

By doubling the improved apparatus employing the invention principle in series or tandem relation the rate of production is doubled, because the cloth gets the same fulling with half the number of nips in each mill and therefore with twice the differential feed in each mill; in this way by using multiple units in series the rate of production can be increased as desired to a capacity sufficient to handle the entire product of a plant, the cuts being put together by sewing and run through the several units of the battery of mills successively and continuously.

The invention process and apparatus have particular advantage where two or more cuts or strings of cloth of different lengths before fulling are run through the mill side by side and simultaneously; in the standard prior type mill where the ends of each piece must be sewed together the longer piece or pieces do not receive as many nips and will not be as completely fulled in a given run as the shorter piece or pieces, and hence the component pieces of the batch are unevenly fulled; whereas in the improved method and apparatus all pieces passing through the mill at once are equally fulled.

As is apparent, once the apparatus is threaded up with a leader or leaders, or strings of cloth being fulled serving the function thereof, no further machine time is lost in loading or unloading; the sewing together of successive cuts is performed while the machine is running; and no taking out of the pieces to turn them end for end, and little or no manipulation of the pieces to change their positions, and no stopping of the mill to measure the degree of fulling is needed, adding to the operating economy of the novel method.

To utilize the invention principle of reversal of cloth travel in practical and commercial use, it is necessary to solve the problem of reversing the travel of the cloth while still retaining the use of the crimp box. The crimp box must be employed in order to effect the lengthwise fulling of the cloth as the rolls perform the widthwise fulling. But the nature of the action of the crimp box in resisting the discharge of the cloth from between the rolls and in causing the cloth to pack into and fill the box in a multiplicity of transverse pleats or folds forbids the simple reversal of the travel of the pair of rolls which are feeding the cloth into the crimp box, because the cloth from within the crimp

box seeks to re-enter the nip of the rolls in transversely folded relation in so thick a bunch that the latter cannot even get to the nip of the rolls, with the result that the travel of the cloth is arrested and the continuing rotation of the rolls burns and chafes the cloth and eventually grinds it in two at this point. Additionally, the engagement of the cloth with the free end of the weighted tongue of the crimp box puts an unwanted drag on the cloth in its travel reversely through the box which tends to stretch the cloth and undo the lengthwise fulling for which the box is intended. To overcome these obstacles to the use of the invention principle, the invention includes the step of getting the folds out of range of the nip of the rolls, as by providing for opening the box, at the instant of reversal, by lifting the tongue or lowering the bottom of the box, thus both eliminating the tongue drag on the fabric, and disposing of the folds by letting them escape and spill out from the delivery end of the box, or alternatively by giving them room to straighten out before reaching the nip of the reversely driven rolls by using a different pair of fulling rolls to effect the reverse travel of the cloth than those employed to pack it into the particular crimping box, this latter pair being separated, preferably accompanied also by release of the tongue's pressure. Through this new step of disposing of the folds and of the tongue drag the reversal principle is made feasible and practicable.

Other aims and advantages of the invention, and the manner of their attainment, are as set forth hereinafter.

Illustrative embodiments of the invention are shown in the accompanying drawings, in which:

Fig. 1 is a diagrammatic elevation showing the practice of the invention through the use of an existing type of fulling mill.

Fig. 10 is a view similar to Fig. 9, showing the same parts in their inactive or waiting position.

Fig. 11 is a plan view on a larger scale of the device of Figs. 9 and 10.

The novel process of the invention admits of being practiced through the use of prior types of roller fulling mills as shown in Fig. 1, by placing two of these standard mills 1, 3, face to face and driving the pair of opposed fulling rolls 5, 7, in each mill continuously and concurrently in the direction to draw the fabric through the rolls of its companion mill. Each mill is equipped with power means for lifting the top roll 5 away from the bottom roll 7, as by known devices such as the fluid-pressure operated cylinders and linkage of U. S. Patent 2,138,597, granted on Nov. 29, 1938 to Ernest Cannity, the top rolls 75 actuated from a source of power 38. The string or

5 being journalled in levers 11 fulcrumed at 13 each having its free end attached to the piston rod 10 of one cylinder 9, and the control valve 15 and fluid-pressure piping of such patent is arranged so that the top roll of each mill is lifted and lowered in alternation with that of the other mill. The control valve 15 is operated through a timer of any known or desired type, either a pair of standard electronic type timers 17 each 10 actuating the other and one thereof actuating a solenoid 19 having a spring-biased armature connected to the control handle 21 of the valve, or of the mechanical type illustrated in Figs. 6 and 7 hereof, or of the electro-mechanical type of Figs. 9-11 hereof, and set to give one mill a greater length of feed than the other.

The cloth is fed back and forth in alternation through the spaced rolls of one mill by the pull of the closed rolls of the other mill, and by reason of the differential extent of feed of the two mills a certain amount of the length of the cloth fails to be retracted into the rolls at the end of each cycle of one forward and one backward feeding, this amount which is left out comprising the constant output of fulled cloth at the end of each cycle or period which is available to be fed directly and continuously into the cloth-washer or other machine performing the next process of a straight-line system or other set-up of the finishing process.

20 As each fulling mill is customarily equipped with a crimp box 23 receiving the cloth discharged by the fulling rolls, which as conventionally designed is not adapted to permit the reverse movement of the cloth, the tongue 25 of each crimp box is connected to the means which lift and lower each top roll, so that the tongue of each crimp box is lifted out of contact with the cloth whenever its associated top roll is lifted out of action, such tongue being correspondingly restored automatically to working position when its associated top roll is again lowered into action, herein by a rod 27 pivoted to the tongue and sliding through a guide in 25 connection with a cross-rod 28 connecting the two levers 11 of each mill, a spring about each rod 27 depressing the tongues yieldingly. The slack of the cloth required to permit backward and forward feed is received alternately in the lower portion of the housing of each mill, and the unretracted yardage representing the output of completely fulled cloth is withdrawn continuously through a port 29 and over a roll 30 at the back of the mill having the greater feed 30 and fed to the next machine in line for further processing. Similar ports and rolls at the back of the other mill admit the fabric in loading the apparatus, and let it run from one mill to the other.

60 In the alternative form shown in Fig. 2, only a single pair of fulling rolls 31, 33, is employed, which are driven concurrently first in a direction to feed the cloth forwardly and then in reverse direction to feed the cloth backwardly. 65 The reversal of rotation and thus of the travel of the cloth is effected by reversing the driving motor 35, by the mechanism illustrated in Fig. 2, or through the use of any other preferred means, such as the measuring roll and mechanical timer of Figs. 3, 6 and 7, or that of Figs. 8-11. In the form Fig. 2, the cloth is fed into the mill by a pair of nip rolls 36 rotated concurrently by a variable speed drive unit 37 of known design containing its own electric driving motor actuated from a source of power 38. The string or

strings of cloth issuing from rolls 36 are threaded through a ring 39 sliding freely between vertical guides 40 and thence enter the nearer crimp box 41 to pass between the fulling rolls and through the farther crimp box 42. The ring 39 with the cloth extending through its gravitates to the lower end of the guides 40 at all times when this stretch of cloth is slack, and thus normally stands below a lever or trip carrying a mercury switch 43 which is open in its resting position. When the length of cloth between nip rolls 36 and fulling rolls 31, 33, is taken up by the rotation of the latter rolls in the forward-feeding direction, sufficiently to lift ring 39 so as to trip the lever in its path and thus to tilt the mercury switch 43, the resultant closing of this switch puts current momentarily via leads 45 through the holding relay or circuit maker of an adjustable electronic timer 44 of known design. This in turn actuates a reversing switch in timer 44 which reverses the direction of rotation of motor 35, and thus feeds the cloth backward, at the same time starting the time delay mechanism of timer 44 to measure off the time for which it is set and upon the expiration of such period to reverse motor 35 again to resume the forward feed of the cloth by rolls 31, 33, with attendant release of the holding relay.

Thus, in use, a suitable length, say 60 yards, of either the leader or the cloth to be fulled is run into the mill through nip rolls 36 and ring 39 by means of the forward-feeding rotation of fulling rolls 31, 33, and then run backward to be deposited on the bottom of the mill between guides 40 and the adjacent end of crimp box 41, with the mercury switch 43 put out of action during the forward feeding. With the mill then put to work and allowed to run continuously starting in the forward-feeding direction, and with the mercury switch 43 in action, this length of cloth will be fed forwardly through the fulling rolls until the final slack therein begins to be taken up and ring 39 is lifted far enough to tilt and close switch 43, whereupon the motor will be reversed and the mill will feed the cloth backward throughout the period for which timer 44 is set, and thereafter fulling rolls 31, 33 will continue to feed the cloth forward and backward automatically.

By virtue of the termination of the forward feed under the control of falling ring 39, all slack cloth between nip rolls 36 and crimp box 41 will always be automatically fed forward by the fulling rolls, regardless of its length and of the amount of backward feed effected by timer 44. This obviates all need for a critical setting of timer 44. The latter is customarily set to produce substantially 60 yards backward feed in fulling 60-yard cuts of cloth.

More important, by driving nip rolls 36 slowly throughout the operation of the mill a differential feed is obtained in which the forward feed exceeds the backward feed by the exact amount of cloth fed into the mill by nip rolls 36 at each cycle, since all the slack cloth available will be taken forward by the fulling rolls in the forward feed, but only the length determined by the setting of timer 44 will be fed back at each cycle. Thus, with nip rolls 36 slowed down through use of the variable speed unit 37 after serving to run the string of cloth into the mill upon starting up, and with these nip rolls set to feed fresh cloth into the mill at the rate of say two yards per cycle, the fulling rolls will feed 62 yards forward and only 60 yards back

at each cycle, on the basis stated. Thus the mill will give a constant output of 2 yards of completely fulled cloth at each cycle. This output of fulled cloth is delivered continuously from the mill by a pair of nip rolls 46 located at the delivery end thereof and driven by shaft 47 from one of the nip rolls 36 and at the proper surface speed.

To open the full crimp box and dispose of its contents upon reversal of the fulling rolls, so as to dispose of the pleats therein and prevent their jamming in the nip of the fulling rolls, with resultant stopping of the cloth travel and abrasion and burning of the cloth, each crimp box, namely the side walls and bottom attached thereto, is pivotally mounted by brackets 48 on the axis of the lower fulling roll 33, while the top or tongue 49 of the box is fixed and stationary at all times. The crimp boxes are respectively attached by rods 50 to pistons working in fluid pressure cylinders 51 and thereby lifted and lowered in alternation, and thus upon reversal of the direction of feed of the cloth the box which has been working and is filled with pleats of cloth is tilted sharply downward to spill out the crimped cloth at the moment of reversal and thereafter to remain wide open so that the cloth may be drawn freely through it to the rolls, the companion box being at the same instant lifted into working relation with its tongue so that the cloth delivered thereinto by the rolls is duly pleated and crimped. Alternatively, the crimp boxes are rigidly mounted with a sharp downward slant away from the rolls, with the tongues respectively connected to the piston rods of the fluid pressure cylinders as in Cannity's U. S. Patent 2,039,882, granted May 5, 1938; so that the tongues are lifted in alternation as the cloth feed is reversed, thus spilling out the folds from the full box in either case. The actuation of the pistons in the two fluid pressure cylinders simultaneously in respectively opposite directions is effected by a 4-way valve 52 supplied with fluid pressure from a suitable source via pipe 53 and connected by pipes 54 with the opposite ends of each cylinder.

To operate 4-way valve 52, the valve control handle 55 is pivoted to the armature of a solenoid 56 connected by leads 57 to timer 44 in such manner that the solenoid is energized to set the valve to lift crimp box 41 and lower crimp box 42 so long as timer 44 runs the motor 35 reversely to feed the cloth backward, the solenoid being deenergized as the reversing switch in timer 44 acts to reverse the motor and start the cloth traveling forward again, whereupon a spring biasing the control handle 55 moves it reversely to cause the fluid pressure to drop crimp box 41 and raise crimp box 42 into action. The operation of the fluid pressure cylinders is identical and obvious when the tongues are made moveable and the boxes fixed in the alternative arrangement.

An adjustable pressure regulator of stock design (not shown) is located in the supply line 53 to the 4-way valve, and thus is used to govern the upward pressure of the box bottoms toward their tongues or the downward pressure of the movable tongues, and the resulting degree of crimping pressure on the cloth.

The alternative form of Figs. 3 to 8 comprises two pairs of opposed rolls 63, 65, the lower member of each pair being mounted in fixed bearings on suitable supports on the machine frame while the upper member of each pair is

rotably mounted by means of its journals in bearings 67 on walking beams 69 fulcrumed on an axis 71 supported in fixed bearings 72 in connection with the frame, in such manner that when one top roll 63 of a pair of opposed rolls is pressed against its companion bottom roll 65 the other top roll is lifted well away from its opposing bottom roll. Chains 73 engaging sprockets fixed on the journals of each pair of opposed rolls and driven by chain 74 and sprockets fixed on the bottom roll shafts and on shaft 75 and continuously driven by electric motor 77 keep the two rolls of each opposed pair rotating continuously in opposite directions at the same surface speed, with capacity for lifting of the top roll a liberal distance away from its companion bottom roll without interrupting the driving. The drive of the left-hand pair of opposed rolls rotates them concurrently to feed the cloth from right to left and thus into crimp box 79, while the corresponding concurrent rotation of the right-hand pair of rolls feeds the cloth from left to right into crimp box 81. In Fig. 3 both pairs of rolls are shown separated, for threading up the machine.

The tongue 83 of each crimp box, weighted as usual by link 85 connected to an arm fixed on rockshaft 87 to which is also fixed the arm 89 supporting the weight rod 91, is connected by linkage to the walking beam carrying the top rolls so that the tilting of the walking beam to separate one pair of rolls lifts the tongue of the crimp box associated with such pair up out of contact with the cloth. For this purpose, arms 93 fixed on the walking beams 69 rotatably support a shaft 95 having fixed thereon a collar 97 into which are screwed the ends of rods 99 each passing through a hole in a rockshaft 101 supported rotatably in short arms 103 fixed on rockshaft 87, with stop nuts on each rod 99 beyond the rockshaft 101. In the reversal of the direction of feed of the cloth which accompanies the tilting of the walking beam, the cloth is drawn without resistance through the now open pair of rolls, and the pleats or folds of cloth within the crimp box adjacent the opened rolls open out and disappear before reaching the nip of the working pair, thus avoiding jamming and burning of the fabric by the presence of such folds at the nip of the working rolls. In certain instances, each tongue 83 is worked by the fluid pressure operated means of Cannity Patent 2,039,882, being lifted and depressed with its associated top roll under control of the 4-way valve described hereinafter.

By thus preferably driving the pairs of rolls continuously, while providing that only one pair can be closed and in feeding relation with the cloth at a time, the loss of energy and time otherwise incident to starting up the idle rolls from rest at each reversal is avoided.

As a very heavy pressure of the rolls 63, 65 against the intervening cloth is required in fulling, sometimes on the order of 1000 pounds pressure, and powerful means for tilting the walking beams to bring the respective top rolls alternately down against their bottom rolls is needed, large fluid-pressure cylinders 105 each having a double acting piston and a piston rod 107 connected to an extension of each walking beam 69 are used, and the fluid under pressure, compressed air, water, oil, or other medium, which propels the pistons alternately in opposite directions is admitted to each cylinder 105 at one side or other of the piston by means of pipes 109 under control of a 4-way

valve 111 supplied through a pressure regulator 113 by pipe 115 from a suitable source (not shown) of fluid under pressure.

This valve 111 is operated by a control handle actuated periodically by any suitable or preferred timer means. Herein, the control handle effects the movement of each piston in alternately opposite directions upon movement of the control handle back and forth throughout a small arc. In this case, and in the form of Fig. 1 also, this movement of the handle must occur at alternately unequal intervals of time in order to impart the differential extents of feed of the cloth in opposite direction required to give the constant output of fulled cloth by the mill. More specifically, the timer is desired to move the control handle in one direction to cause the reversal of travel of the cloth at the end of a predetermined length of feed in the forward direction, and then to move the control handle in the opposite direction to again reverse the travel of the cloth at the end of a predetermined extent of backward feed of the cloth which is less than the extent of forward feed, the extent of feed in the two directions remaining constant though unequal and alternate. In addition, the timer means must provide for adjustment, i. e., variation, of the extent of the feed in either of the two directions to suit the needs of the cloth. To these ends, a mechanical type of timer measuring the actual travel of the cloth in each direction is provided, comprising a measuring roll 119 having a rough friction surface such as card clothing and mounted in fixed bearings in connection with the supporting framework of the machine, with an opposing press roll 121 movably mounted on arms pivoted in the frame and pressed by springs yieldingly toward the measuring roll to hold the cloth in non-slipping relation to the surface of the latter roll. The extended shaft on which the measuring roll 119 is fixed has a sprocket fixed on its extremity which is connected by chain 123 to drive a Reeves type variable speed driving unit 125 which in turn drives by chain 127 a sprocket 129, Figs. 6 and 7, fixed on a jackshaft 131 rotating in bearings on frame members 133. A gear 135 fixed on jackshaft 131 meshes with a larger gear 137 fixed on the end of a stub shaft 139 rotating in bearings 141 on one end of a lever 143 revolving freely by means of its hub 145 about a sleeve 146 fixed by screw 148 on jackshaft 131. A smaller gear 147 fixed on the other end of the stub shaft meshes with a large gear 149 fixed on the hub of a worm gear 151 rotating freely on sleeve 146, the worm gear engaging with a worm 153 on a shaft 155 mounted in bearings 157 on the frame and rotated by a variable speed drive 158 driven by chain and sprockets from one lower fulling roll shaft 160.

The longer end of arm 143 carries a striker 159 which engages the free end of an actuating member 161 for operating the control handle 117 of 4-way valve 111. This member 161 has a hub fitting freely on the prolonged valve control shaft on which control handle 117 is fixed, the hub of the actuating member being retained thereon by a washer and screw 163. Member 161 has spaced lugs 165 projecting into the plane of handle 117 and actuating the latter with lost motion, a pull spring 167 being connected to a pin fixed near the top of member 161 and anchored to the supporting structure at 169 giving the member 161 a quick throw as soon as it is pushed past center by the striker 159, thus

guarding against breakage of parts upon delayed reversal of the cloth-driving mechanism. A brace 171 fitting freely around the hub of actuating member 161 and bolted to the supporting framework, supports the outer end of the valve control shaft.

The measuring roll 119 when propelled in either direction by the cloth transmits to the planetary gear 147 of the differential gearing just described a rotation which causes it to travel around the slow moving gear 149 on the hub of the worm gear 151 and thereby causes the arm 143 to revolve about the axis of the jackshaft 131 until its striker 159 strikes and moves member 161 into one of its extreme positions and thus 15 throws the control lever 117 of the 4-way valve, thus relieving the pressure on one side of the piston in each cylinder 105 and applying fluid pressure to the other side thereof to cause movement of the pistons which reverses the slant of the walking beams and brings the idle pair of continuously rotating fulling rolls into driving relation with the cloth, thereby feeding the latter in the opposite direction. Since the measuring roll 119 is then rotated by the cloth in the opposite direction to that described, the arm 143 is likewise revolved in the opposite direction until its striker again strikes member 161, throwing the control handle of the 4-way valve to its other extreme position and reversing the pressure on the pistons to tilt the walking beams again. Because the worm gear 151 is being constantly revolved in one direction by the continuous drive of unit 158, its motion adds to the number of revolutions of the measuring roll required to make the arm 143 perform the slightly more than one revolution required to actuate the valve when the cloth is traveling in the forward direction, but reduces the number of revolutions of the measuring roll to complete the travel of the arm to reverse the valve again when the cloth is traveling in the backward direction, thus achieving the differential feed of the cloth in its two directions of travel which produces the "pilgrim's step" advance thereof and the continuous output of fullled cloth.

Adjustment of the differential, i. e., the excess or gain of the forward feed over the backward feed, is effected by speeding up or slowing down the drive of the worm shaft through manipulation of the variable speed drive 158. The slower the worm shaft is driven the more nearly equal become the advance and retreat of the cloth, while by speeding up the worm shaft the forward feed is increased and the backward feed is correspondingly reduced. With the worm wheel left stationary, the feed forward and back is equal, with no differential.

As is obvious, a single discontinuous actuation of the worm shaft at the proper time and in the proper direction at any point in the cycle of one forward and one backward feed gives the same result of lengthening the time taken by the arm to make its circuit in one direction over that required to complete its travel in the reverse direction, and thus of increasing the extent of feed of the cloth forward relatively to the extent of backward feed. Thus any suitable or desired form of intermittent drive for the worm shaft of adjustable scope, such as a pawl and ratchet, functioning at least once during each cycle of back and forth feed of the cloth to advance the worm shaft the desired amount, attains the same results as the variable speed drive.

The mill is provided with a housing with side

75

walls and a bottom. The cloth is in this instance put straight through the mill in a straight pass with no looping; the leading portion 173 of the cloth, i. e., that which is emitted from the fulling rolls in either direction of the travel, is guided out of the fulling mill and into a scray 175 located at each end of the mill, by a roll 177 mounted in bearings on each end wall of the mill and constantly driven by chain 179 and sprockets from the nearer bottom roll shaft in a direction to carry the cloth out of the mill. Each scray thus in turns forms a reservoir to hold the slack needed to permit the cloth to be fed back and forth through the rolls.

Figs. 8 to 11 show an alternative electro-mechanical timer applied to the same mill as is shown in Figs. 3 to 5. This arrangement employs the rising and falling ring 39 and tilting mercury switch 43 of Fig. 2 to terminate the forward feed by the right-hand pair of rolls 63, 65, Fig. 3, and a mechanically propelled timing device driven from the lower left-hand fulling roll 65 by means of a sprocket on the outer end of shaft 66 thereof and chains 181, 183, with intervening large and small sprockets rotating in unison on jackshaft 185, to terminate the backward feed by the other pair. As shown in Figs. 9 to 11, this mechanical timer comprises a large sprocket 181 engaged by chain 183 and driving a shaft 189 of a worm type reduction gearing 191 of known commercial form to rotate at greatly reduced speed and at fixed ratio a shaft 193 on which is fixed a ratchet wheel 195. An arm 197 swinging free on shaft 193 carries a pawl 199 pivoted at 201 therein which engages upon occasion with the teeth of counterclockwise rotating ratchet wheel 195 to carry the pawl and arm around with the ratchet wheel. This motion brings the notched tail 203 of the pawl into displacing contact with the operating arm 205 of a limit switch 207 to open this switch, and also brings the notch 209 in the tail of the pawl into engagement with the hooked end 211 of a detent 213 pivoted at 214, a tension spring 215 provided with screw tension-adjusting means 217 biasing the detent so that its hooked end 211 tends to stay elevated in a position maintaining its engagement with notch 209 of the pawl to hold the tail 203 of the pawl in switch closing relation against lever 205 of switch 207. As the pawl engages switch lever 205 and the hook 211 of the detent, a stop pin 219 engages the beveled end of the pawl to depress this end and thus rock the pawl counterclockwise on its pivot 201 to withdraw it from engagement with the teeth of ratchet 195.

This timer determines the length of reverse feed of the cloth. The forward feed, just as in Fig. 2, is determined by the rising and falling ring 39, which permits all slack cloth in the mill between the forward-feeding rolls and the input-rolls 36 propelled by variable speed drive 37 to be fed forward until ring 39 is lifted with accompanying tilting of switch 43. During this forward feed the parts stand as in Fig. 10, with the pawl held by the detent and both switches 43 and 207 open. As ring 39 is lifted, however, the resultant momentary closing of mercury switch 43 energizes a solenoid 221 in circuit therewith, which attracts the tail of detent 213, lifting it into the position of Fig. 9 and causing its hooked end to descend out of the notch 209, releasing pawl 199 and permitting arm 197 to recoil clockwise under the influence of its coil spring 223 until the pawl strikes a stop 225 which deflects its toothed end into engagement with the slowly

rotating ratchet 195. This releases lever 205 of the limit switch 207 from the pressure of the tail of the pawl, and switch 207 thereupon closes its circuit via wires 227 to energize a solenoid 229 whose armature is connected by link 231 to the operating lever 233 of valve 111 feeding compressed air via pipes 109 to the cylinders 105 which tilt the walking beam 69. When solenoid 229 is thus energized its armature is lifted to raise control lever 233 to admit compressed air above the piston in cylinders 105, which thereupon draw down the left-hand end of walking beam 69 to separate the forward-feeding fulling rolls and bring the backward-feeding pair into driving engagement with the cloth so as to reverse the cloth travel.

This condition of reverse feed prevails until pawl 199, lifted slowly by ratchet 195, again makes contact with lever 205 of limit switch 207 and is seized by hook 211 of the detent and is thrown out of engagement with the ratchet teeth by striking pin 219. The resulting opening of limit switch 207 through this contact of the pawl de-energizes solenoid 229 and its armature drops under gravity depressing control lever 233 of the valve to admit air below the piston in cylinders 105 so as to again tilt the walking beam 69, thus separating the backward-feeding rolls and bringing the forward-feeding pair into action again to propel the cloth forwardly. The cycle of forward feed followed by backward feed of the cloth is thus completed, and the parts of the timer stand in the waiting position of Fig. 10 until all the slack cloth in the machine has again been fed forward, this cycle repeating itself with alternate forward and backward feed.

To attain the differential feed, with the travel of the cloth in the forward direction a few yards in excess of the reverse feed, it is necessary only to adjust the variable speed drive 37 governing the rate of input of the rolls 36 so as to feed into the mill during each cycle the same yardage of cloth desired to be delivered in fulled condition from the other end of the machine at each cycle. Thus, with the stroke of the pawl arm 197 adjusted by moving stop pin 225 along its slot 235 so as to give a reverse feed of, say, 60 yards, and with falling ring 39 automatically feeding forward all slack cloth in the mill at each forward-feeding operation, an input of 2 yards per cycle by the rolls 36 gives a forward feed of 62 yards, leaving an unreturned extent of 2 yards, less the shrinkage, to be taken from the mill at each cycle as completely fulled cloth.

In a straight-line cloth-finishing process, now made possible by the use of any one of the novel machines, the cloth is put together in continuous relation by sewing the leading end of each cut to the trailing end of the preceding cut and is fed through the successive machines in advance of the fulling mill, and the soaper or other machine immediately preceding the fulling mill discharges its output into a scray such as 175 located between it and the fulling mill, in the case of Fig. 3. When slightly more than the yardage adopted for the forward feed of the mill has been received in the scray, the mill is started with the fulling rolls feeding the cloth in the forward direction, and the cloth is fed forward and backward, discharging on each cycle more cloth into the delivery scray 175 than is taken back therefrom and transferred to the feed-end scray, this excess being drawn forwardly and fed continuously into the washer or other machine comprising the first of a succeeding series of machines

performing the other finishing operations on the cloth. In the form of Fig. 8, the cloth being run back and forth stays within the mill, being piled on the housing floor beneath the guide rolls at the delivery ends of the respective crimp boxes, except the yardage of completely fulled cloth being taken out by the delivery rolls which correspond to 46 of Fig. 2; while the cloth supplied by the feed rolls 36 lies on the floor outside the housing until drawn in through falling ring 39 at the end of each forward feed. In this way the entire finishing process or as much thereof as is desired is performed as one continuous or straight-line process, overcoming the hitherto inescapable break in the continuity of finishing compelled by the use of batch type mills, in the working of which no cloth is gotten out of the mill until the entire batch is done and then the entire contents are unburdened at once.

Where a plurality of strings of cloth are run through the novel apparatus side by side, the subsequent machines in the straight-line process which are not capable of handling more than one string are duplicated and located abreast of each other in the series, and the strings of cloth separated and each sent through its proper machine to effect this particular stage in the finishing.

While I have illustrated and described certain forms in which the invention may be embodied, I am aware that many modifications may be made therein by any person skilled in the art, without departing from the scope of the invention as expressed in the claims. Therefore, I do not wish to be limited to the particular forms shown, or to the details of construction thereof, but what I do claim is:

1. In a cloth fulling mill, in combination, opposed rolls squeezing the cloth between them, means driving the rolls to feed the cloth therethrough first in one direction of its length and then in the opposite direction of its length, and a crimp box at each side of the rolls.

2. In a cloth fulling mill, in combination, opposed rolls squeezing the cloth between them, means driving the rolls to feed the cloth therethrough first in one direction and then in the opposite direction, a crimp box at each side of the rolls, and means putting the crimp boxes alternately and successively into action.

3. In a cloth fulling mill, in combination, opposed rolls squeezing the cloth between them, means driving the rolls to feed the cloth therethrough first in one direction and then in the opposite direction, a crimp box at one side of the rolls crimping the emerging cloth into transverse folds, and means emptying the folds from the crimp box upon reversal of the direction of travel of the cloth.

4. In a cloth fulling mill, in combination, opposed rolls squeezing the cloth between them, means driving the rolls to feed the cloth therethrough first in one direction and then in the opposite direction, a crimp box at one side of the rolls having a tongue and crimping the emerging cloth, means moving the rolls apart, and means connected to the latter roll-moving means shifting the tongue into inoperative position.

5. In a cloth fulling mill, in combination, opposed rolls squeezing the cloth between them, means driving the rolls to feed the cloth therethrough first in one direction and then in the opposite direction, a crimp box at each side of the rolls crimping the cloth emerging from between the rolls into transverse folds, and means emptying the folds from each crimp box in turn

as the direction of feed of the cloth is reversed.

6. In a cloth fulling mill, in combination, opposed rolls squeezing the cloth between them, means driving the rolls to feed the cloth therethrough first in one direction and then in the opposite direction, a crimp box at each side of the rolls crimping the cloth emerging from between the rolls into transverse folds, and having a fold-supporting surface capable of being tilted downward to release the folds and remove them from proximity to the rolls, and means bringing about the said tilting and removal as the direction of feed of the cloth is reversed.

7. In a cloth fulling mill, in combination, opposed rolls squeezing the cloth between them, means driving the rolls to feed the cloth therethrough first in one direction and then in the opposite direction, a crimp box at each side of the rolls crimping the cloth emerging from between the rolls into transverse folds, and means acting when the direction of feed is reversed to open one box and release the folds therefrom and close the other box.

8. In a cloth fulling mill, in combination, opposed rolls squeezing the cloth between them, means driving the rolls to feed the cloth therethrough first in one direction and then in the opposite direction, a crimp box at each side of the rolls crimping the cloth emerging from between the rolls into transverse folds, and having a fixed surface pressing down on the cloth and a movable surface pressing upwardly against the cloth, and means effecting the lowering of the movable surface of one box to spill out the folds held therein and the raising of the movable surface of the other box into crimping relation when the direction of travel of the cloth is reversed.

9. In a cloth fulling mill, in combination, opposed rolls squeezing the cloth between them, means driving the rolls to feed the cloth therethrough, and means actuated by the travel of the cloth effecting the feed of the cloth in one direction to a given extent and then in the opposite direction to a different extent.

10. In a cloth fulling mill, in combination, two pairs of opposed rolls squeezing the cloth, means driving one pair to feed the cloth in one direction, means driving the other pair to feed the cloth in the opposite direction, and means bringing the pairs of rolls alternately and successively into feeding engagement with the cloth.

11. In a cloth fulling mill, in combination, two pairs of continuously rotating opposed rolls squeezing the cloth, each pair feeding the cloth in the opposite direction to the other, means closing one pair upon the cloth while opening the other pair, and means reversing the relative open and closed relation of the two pairs to the cloth.

12. In a cloth fulling mill, in combination, two pairs of continuously rotating opposed rolls squeezing the cloth, each pair pulling the cloth through the other pair, and means alternately closing each pair in turn upon the cloth while simultaneously opening the other pair.

13. In a cloth fulling mill, in combination, two pairs of continuously rotating opposed rolls squeezing the cloth, each pair pulling the cloth through the other pair, means alternately closing each pair in turn upon the cloth while simultaneously opening the other pair, and a crimp box receiving the cloth as it is discharged from each pair of rolls.

14. In a cloth fulling mill, in combination, two

pairs of continuously rotating opposed rolls squeezing the cloth, each pair pulling the cloth through the other pair, means alternately closing each pair in turn upon the cloth while simultaneously opening the other pair, a crimp box receiving the cloth as it is discharged from each pair of rolls, each crimp box having a movable tongue, and means automatically moving the tongue of the crimp box which is in non-receiving relation into inoperative relation with the cloth, and moving the tongue of the crimp box receiving the cloth into working position, as the direction of travel of the cloth is reversed.

15. In a cloth fulling mill, in combination, opposed rolls squeezing the cloth between them, means driving the rolls to feed the cloth therethrough, means automatically reversing the direction and extent of the feed of the cloth by the rolls, a crimp box at each side of the rolls receiving in alternation the cloth as it is discharged by the rolls, and means putting one crimp box into working relation and the other crimp box in cloth-freeing relation as the direction of feed of the cloth is reversed.

16. In a cloth fulling mill, in combination, opposed rolls squeezing the cloth between them, means driving the rolls to feed the cloth therethrough, a roll rotated by the traveling cloth, means reversing the direction of travel of the cloth, and means actuated by the cloth-driven roll actuating the reversing means after unequal extents of travel of the cloth in the two directions.

17. In a cloth fulling mill, in combination, opposed rolls squeezing the cloth between them, means driving the rolls to feed the cloth therethrough, a roll rotated by the traveling cloth, means reversing the direction of travel of the cloth, and differential motion means actuated by the cloth-driven roll and operating the reversing means at the end of a greater extent of feed of the cloth in the forward direction and a lesser extent of feed in the reverse direction.

18. A method of fulling cloth by opposed rolls and crimp boxes which includes the steps of feeding the cloth through the nip or nips of the rolls and a crimp box in the forward direction for a portion of the length of the cloth, then feeding the cloth through the nip of the rolls and a crimp box in the reverse direction for a distance less than the forward feed, then again feeding the cloth forward as before and so on in alternate directions.

19. A method of fulling cloth by opposed rolls and crimp boxes which includes the steps of feeding the cloth back and forth through the nip or nips of the rolls and the crimp boxes, with the forward feed in excess of the backward feed.

20. A method of fulling cloth by opposed rolls which includes the steps of feeding the cloth back and forth through the nip or nips of the rolls, with the forward feed in excess of the backward feed, and attaching a leader to each end of the cloth to guide these ends back and forth through the nip of the rolls.

21. A method of fulling cloth by opposed rolls which includes the steps of feeding the cloth back and forth through the nip or nips of the rolls, with the forward feed in excess of the backward feed, using a portion of the cloth to be fulled as a leader, and transferring this portion to the trailing end of the cloth to render the fulling thereof uniform throughout its length.

22. A method of fulling cloth by opposed rolls which includes the steps of feeding the cloth back

and forth through the nip or nips of the rolls, with the forward feed in excess of the backward feed, employing a portion of the cloth to be fulled of at least the length of the backward feed as a leader, transferring this portion to the trailing end of the cloth being fulled, and allowing this portion to be fed back and forth through the nip of the rolls until a length thereof equal to the length of the backward feed has passed the rolls.

23. Feeding devices for continuous material having in combination rolls propelling and working on the material, feed rolls feeding the material relatively to the working rolls, and means actuated by the pull of the working rolls on the portion of material engaged by the feed rolls arresting the propelling action of the working rolls.

24. In a cloth fulling mill, in combination, fulling rolls propelling the cloth, feed rolls feeding the cloth relatively to the fulling rolls, and means actuated by the taking-up of the slack in the cloth between the fulling rolls and the feed rolls reversing the fulling rolls.

25. In a cloth fulling mill, in combination, fulling rolls propelling the cloth, feed rolls feeding the cloth relatively to the fulling rolls, a member actuated by the cloth as the fulling rolls take up the slack between themselves and the feed rolls, and means put in actuation by the actuation of such member causing the reversal of the fulling rolls.

26. In a cloth fulling mill, in combination, fulling rolls propelling the cloth, feed rolls feeding the cloth relatively to the fulling rolls, a member having a passage through which the cloth travels in its course between the feed rolls and the fulling rolls, guides supporting such member for gravitating movement, and means reversing the direction of propulsion of the cloth by the fulling rolls and actuated by the lifting of such member by tension on the cloth passing therethrough.

27. In a cloth fulling mill, in combination, opposed rolls squeezing the cloth between them, a crimp box at each side of the rolls, and means driving the rolls to effect the feed of the cloth in one direction to a given extent and then reversing the rolls to effect the feed of the cloth in the opposite direction to a different extent.

28. In a cloth fulling mill, in combination, opposed rolls squeezing the cloth between them, a crimp box at each side of the rolls, means driving the rolls to feed the cloth therethrough, means causing the rolls to propel the cloth alternately in opposite directions, and timing means rendering unequal the duration of the driving in the respective opposite directions.

29. In a cloth fulling mill, in combination, fulling rolls propelling the cloth, feed rolls feeding the cloth at a lesser rate than the fulling rolls, and means reversing the direction of propulsion of the cloth by the fulling rolls when the latter take up the slack between themselves and the feed

rolls and again reversing the direction of propulsion after a predetermined interval of travel of the cloth.

30. In a cloth fulling mill, in combination, fulling rolls propelling the cloth, feed rolls feeding the cloth relatively to the fulling rolls, timer means effecting the propelling of the cloth in one direction for a predetermined distance and thereafter reversing the direction of feed of the cloth, and means actuated by tension on the cloth setting the timer means in action.

31. In a cloth fulling mill, in combination, fulling rolls propelling the cloth, feed rolls feeding the cloth relatively to the fulling rolls, timer means effecting the propelling of the cloth in one direction for a predetermined distance and thereafter reversing the direction of feed of the cloth, and feeler means responding to tension on the cloth between the feed rolls and the fulling rolls by setting the timer means in action.

32. In a cloth fulling mill, in combination, fulling rolls propelling the cloth, feed rolls feeding the cloth relatively to the fulling rolls, timer means effecting the propelling of the cloth in one direction for a predetermined distance and thereafter reversing the direction of feed of the cloth, feeler means responding to tension on the cloth between the feed rolls and the fulling rolls by setting the timer means in action, and means varying the rate of feed of the feed rolls and thus determining the excess of feed of the cloth in one direction over that in the other direction.

33. A method of fulling cloth by opposed rolls feeding the cloth which includes the steps of feeding a predetermined length of the cloth thereby in one direction and then reversing the direction of feed until all available slack in the cloth ahead of the rolls has been taken up, and then again reversing the direction of feed for a predetermined extent of feed, and so on in alternation.

34. A method of fulling cloth in a fulling mill by opposed rolls feeding the cloth which includes the steps of feeding the cloth into the mill at a predetermined rate, feeding a predetermined length of the cloth in one direction by the fulling rolls and then reversing the direction of feed until all available slack between the fulling rolls and the point of entry of the cloth into the mill has been taken up, and then again reversing the direction of feed for a predetermined extent of feed, and so on.
